UNITED STATES PATENT OFFICE

155,735

DESIGN FOR A FLUORESCENT LIGHTING FIXTURE

Donald F. Russell, Newburyport, Mass., assignor
to Sylvania Electric Products Inc., Salem, Mass.,
a corporation of Massachusetts

Application September 12, 1947, Serial No. 141,358

Term of patent 14 years

(Cl. D48—23)

To all whom it may concern:

Be it known that I, Donald F. Russell, citizen of the United States, residing at Newburyport in the county of Essex and State of Massachusetts have invented a new, original, and ornamental Design for a Fluorescent Lighting Fixture, of which the following is a specification, reference being had to the accompanying drawing, forming part thereof.

The figure is a perspective view of a fluorescent lighting fixture, showing my new design.

I claim:

The ornamental design for a fluorescent lighting fixture, as shown.

DONALD F. RUSSELL.
